UNITED STATES PATENT OFFICE

1,923,910

PRINTING PRESS

Martin W. Brueshaber, River Forest, Ill., assignor
to The Goss Printing Press Co., Chicago, Ill., a
Corporation of Illinois

Application July 29, 1932. Serial No. 625,723

17 Claims. (Cl. 101—180)

My invention relates to printing presses and has for its object the provision of a new and improved form and arrangement of auxiliary printing means for applying color printing upon both 5 faces of any selected one of the several webs from the different press units at selected portions of said web. It is one of the objects of my invention to provide an arrangement of this type comprising means for slitting the selected web longitudinally and applying color printing upon one face of 10 one web portion for providing a colored outside page and applying color printing upon the opposite face of the other web portion for providing a colored inside page.

15 It is one of the objects of my invention to provide an improved arrangement of impression cylinder means and co-operating form cylinder means by reason of which the opposite end portions of said cylinders at opposite sides of the press are adapted to operate in opposite directions 20 for effecting the desired printing on opposite faces of parallel arranged web portions without the necessity for shifting either of the web portions transversely or otherwise diverting such web portion 25 from its normal straight run by means of angle bars or the like.

It is one of the objects of my invention to provide an improved arrangement of auxiliary printing means of this type in which the form and the 30 impression cylinders at opposite sides of the press are supported by the same transverse shafts, with the cylinders at one side of the press revolubly mounted upon the shafts while each of the cylinders at the opposite side of the press is rotatable 35 with the shaft by which it is supported, means being preferably provided for driving the loosely mounted cylinder members by power from one or more of the shafts by which such cylinders are supported.

40 It is another object of my invention to improve devices of this type in sundry details with respect to the inking mechanism and other parts as hereininafter specifically described. The preferred means by which I have accomplished my several 45 objects are illustrated in the drawings and are hereininafter specifically described. That which I believe to be new and desire to cover by Letters Patent is set forth in the claims.

50 In the drawings,—

Fig. 1 is a diagrammatic view showing a portion of a unit type of newspaper printing press showing the preferred form of my improved color printing mechanism in connection therewith, 55 parts of the framework being broken away and

many of the operating parts being omitted for clearness of illustration.

Fig. 2 is a top plan view of the auxiliary printing mechanism, partially broken away, and with the inking mechanisms omitted.

Fig. 3 is a view showing a portion of one of the inking mechanisms in connection with the auxiliary printing arrangement, Fig. 3 showing the parts substantially as seen at line 3—3 of Fig. 1.

Fig. 4 is a vertical cross-section taken at line 65 4—4 of Fig. 2.

Fig. 5 is a face view showing the arrangement of the driving gears as seen at line 5—5 of Fig. 2; and

Fig. 6 is a vertical cross-section taken at line 70 6—6 of Fig. 2.

Referring now to the several figures of the drawings, in which corresponding parts are indicated by the same reference characters, 10, 11 and 12 indicate unit press frames each having two 75 printing couples mounted thereon, each of which printing couples comprises an impression cylinder 13 and a form cylinder 14. In the arrangement shown, the several press units are arranged side by side in alignment with each other, the 80 unit frames 10, 11 and 12 being connected at their upper ends by longitudinally extending frame bars 15. Each of the press units is equipped with the ordinary operating mechanism 85 for perfecting a web, the greater part of such mechanism being omitted for clearness of illustration. In the arrangement shown webs 16, 17 and 18 are shown being perfected by the respective units. A framework 19 is shown rising from the longitudinally extending frame bars 15 at one 90 end of the portion of the press shown, such framework 19 being provided for a folding mechanism of any approved type.

In the arrangement shown in Fig. 1, the showing is quite diagrammatic, no framework being 95 included for the auxiliary printing means. It will be understood that the operative parts comprising the auxiliary printing mechanism are supported by any suitable framework, portions of which are shown in Figs. 2 and 6.

Above the units comprising the unit frames 10, 11 and 12 I have mounted a heavy shaft 20 in position parallel with the cylinders 13 and 14 and directly thereabove so that any one of the webs 16, 17 or 18 can be directed to the auxiliary printing mechanism carried by shaft 20 and its associated supporting means. Upon the shaft 20 I have mounted impression cylinders 21 and 22 (see Fig. 2), the cylinder 21 being keyed upon the shaft 20 as shown in Fig. 6, while the cylinder 105 110

22 is revolutely mounted with respect to said shaft.

In spaced relation about the shaft 20 and the cylinders 21 and 22, I have provided a set of 5 heavy shafts 23, 24, 25 and 26, upon each of which are mounted two form cylinders in end to end relation, as is clearly shown in Fig. 2. In the arrangement shown, the form cylinders upon the shaft 23 are indicated by the numerals 27 10 and 28; those upon the shaft 24 by the numerals 29 and 30; those upon the shaft 25 by the numerals 31 and 32, and those upon the shaft 26 by the numerals 33 and 34. As is clearly shown in Fig. 6, the cylinders 27 and 33 are keyed upon 15 the shafts 23 and 26 respectively, and the cylinders 29 and 31 are in like manner keyed upon the shafts 24 and 25. Each of the cylinders 28, 30, 32 and 34 is revolutely mounted with respect to the shaft upon which it is mounted and by 20 which it is supported as above set forth.

As is clearly shown in Fig. 2, the shafts 20, 23, 24, 25 and 26 are connected together for rotation in cooperative relation by means of gears 35, 36, 37, 38 and 39 respectively, by which the cylinders 25 are caused to rotate in co-operative relation as indicated by the arrows thereon in said Fig. 2. Power is applied for driving the gear 35 preferably by means of a spur gear 40 meshing with the gear 35 (see Fig. 2), such spur gear 40 being 30 driven by short shaft 41 which in turn is driven by a shaft 42 connected thereto by means of beveled gears 43.

The means provided for driving the cylinders 22, 28, 30, 32 and 34 comprises a gear 44 keyed 35 upon the opposite end of the shaft 20 from that at which the gear 35 is mounted, such gear 44 meshing with an idler gear 45 which in turn meshes with a gear 46 mounted upon a short shaft 47 which at its inner end is provided with a gear 48. The gear 48 in turn meshes with a gear 49 connected with the cylinder 22 by means of a sleeve 50, the arrangement being such that the cylinders 21 and 22 are driven at the same 40 speed but in the opposite directions. The cylinders 28, 30, 32 and 34 are driven in cooperative relation with respect to the cylinder 22 by means of gears 51, 52, 53 and 54 which are connected respectively with the cylinders by means of sleeves 55, 56, 57 and 58. The direction of rotation of the impression cylinder 22 and the form cylinders 28, 30, 32 and 34 is indicated by the 45 arrows thereon in Fig. 2, each of such arrows being in the reversed direction from that of the arrow indicating the direction of rotation of the corresponding cylinder at the opposite side of the press.

In the arrangement shown, the gear 45 is supported by a short shaft 45a, the arrangement being such that the gear is slidable along the shaft out of mesh with the gears 44 and 46. Power may then be applied to the gear 49 for driving it in the same direction as that in which the shaft 20 rotates, so as to provide for rotation 60 of the cylinders 21 and 22 in the same direction when such operation may be desired.

An additional set of heavy shafts is provided in spaced relation to each other about the shaft 20 and at a greater distance therefrom than the shafts 23, 24, 25 and 26, such additional shafts being indicated by the numerals 59, 60, 61 and 62. Upon each of said additional shafts I have provided ink drums 63 and 64 in end to end relation, as is best shown in Fig. 3 in connection with the shaft 60. About each of the shafts 75 59, 60, 61 and 62, I have provided a plurality of

shafts 65 and 66 in spaced relation to each other about the ink drums 63 and 64, such shafts 65 and 66 having ink rollers mounted thereon for applying ink to the ink drum and from said drum to the form cylinder in accordance with ordinary practice. As is best shown in Fig. 3, the ink rollers mounted upon the shafts 65 are located at one side of the press, being indicated by the numerals 67, while the ink rollers mounted upon the shafts 66 are at the opposite side of the press, being indicated by the numerals 68. One of the rollers 67 is mounted in an ink fountain 69, and one of the rollers 68 is mounted in an ink fountain 70. In the arrangement shown the shafts 65 and 66 arranged closest adjacent to the form cylinder are provided with rollers 67 and 68 at both sides of the press. The arrangement is such that ink is taken from the fountains at both sides of the press and distributed evenly upon the form cylinders for an outside face printing upon the web portion at one side of the press and an inside face printing upon the web portion at the opposite side of the press.

By the use of my improved arrangement, in which any one of the webs perfected by the several press units may be led about the impression cylinders 21 and 22, the desired color printing may be effected upon selected portions of either one or two webs as may be desired. In the arrangement shown in Fig. 1, the web 16 from the press unit 10 is carried about a roller 71 which is provided with a rotary slitter 72 by which the web 16 is divided into two portions 73 and 74, one portion of which goes toward the right in Fig. 1 to one face of the impression cylinders and the other of which trends toward the left to the opposite face of the impression cylinders. The web portion 73 is then brought down about rollers 75 and 76 so as to pass toward the right along with webs 17 and 18, while the complementary web portion 74 is brought down from the impression cylinder about rollers 77 and 78 and thence upwardly about rollers 79 and 80 into position again alongside the web portion 73.

When it is desired to provide color on the web 120 17 in lieu of the color printing on web 16 as above explained, the web 17 is run as shown in Fig. 1, the web 17 is routed about the roller 71 for delivery to the auxiliary printing cylinders, and the web 16 is then run upwardly and toward 125 the right by the use of rollers 81. If it were desired to run the web 18 through the auxiliary printing mechanism, both of the webs 16 and 17 would be directed around the auxiliary printing mechanism by use of the rollers 81.

While I prefer to employ the form of construction as shown in my drawings and as above described, it will be understood that my invention is not to be limited thereto except so far as the 135 claims may be so limited by the prior art, since it is evident that changes might well be made in the arrangement of the parts without departing from my invention.

I claim:—

1. In a printing press, the combination of 140 a plurality of press units each comprising two printing couples for printing both faces of a web, an auxiliary impression cylinder and a plurality of co-operating form cylinders in spaced relation to each other about said impression cylinder at one side of the press for making an outside face color printing on a portion of any selected one of the webs from said press units, a second auxiliary impression cylinder and a plurality of co-operating 145 form cylinders in spaced relation to each other

- about said impression cylinder at the opposite side of the press in axial alignment respectively with the first named auxiliary cylinders and in position to make an inside face color printing on a complementary web portion from said press units, and means for driving said auxiliary cylinders serving to rotate the cylinders at one side of the press in the reverse direction from that of those at the opposite side of the press. 80
- 10 2. In a printing press, the combination of a plurality of press units each comprising two printing couples for printing both faces of a web, an auxiliary impression cylinder and a plurality of co-operating form cylinders in spaced relation to each other about said impression cylinder at one side of the press for making an outside face color printing on a portion of any selected one of the webs from said press units, a second auxiliary impression cylinder and a plurality of co-operating form cylinders in spaced relation to each other about said impression cylinder at the opposite side of the press in axial alignment respectively with the first named auxiliary cylinders and in position to make an inside face color printing 85
- 15 on a complementary web portion from said press units, and means for driving said auxiliary cylinders at one side of the press at the same speed as that at which the corresponding cylinders are driven at the opposite side of the press but in the reverse direction. 90
- 20 3. In a printing press, the combination of a plurality of press units each comprising two printing couples for printing both faces of a web, auxiliary impression cylinders located at opposite sides of the press in alignment with each other, a plurality of co-operating form cylinders at each side of the press in spaced relation to each other about said impression cylinders with the form cylinders at one side of the press in alignment 95
- 25 respectively with the form cylinders at the opposite side of the press, means for driving said auxiliary cylinders at each side of the press in co-operative relation, with the cylinders at one side of the press rotating in the opposite direction from that of those at the opposite side of the press, and a roller revolvably mounted alongside of said impression cylinders for delivery of a web portion to one face of one of said cylinders for 100
- 30 passage thereabout in one direction and for delivery of a web portion to the other face of the other of said cylinders for passage thereabout in the opposite direction. 105
- 35 4. In a printing press, the combination of a plurality of press units each comprising two printing couples for printing both faces of a web, auxiliary impression cylinders located at opposite sides of the press in alignment with each other, a plurality of co-operating form cylinders at each side of the press in spaced relation to each other about said impression cylinders with the form cylinders at one side of the press in alignment 110
- 40 respectively with the form cylinders at the opposite side of the press, means for driving said auxiliary cylinders at each side of the press in co-operative relation, with the cylinders at one side of the press rotating in the opposite direction from that of those at the opposite side of the press, and a roller revolvably mounted alongside of said impression cylinders for delivery of a web portion to one face of one of said cylinders for 115
- 45 passage thereabout in one direction and for delivery of a web portion to the other face of the other of said cylinders for passage thereabout in the opposite direction. 120
- 50 5. In a printing press, the combination of two impression cylinders in axial alignment with each other in closely spaced relation, form cylinders in axial alignment with each other and also in closely spaced relation to each other in position to cooperate with the impression cylinders respectively, and means for driving said cylinders serving to drive one set of cooperating cylinders in one direction and to drive the other set of cooperating cylinders in the opposite direction. 125
- 55 6. In a printing press, the combination of two impression cylinders in axial alignment with each other in closely spaced relation, form cylinders in axial alignment with each other and also in closely spaced relation to each other in position to cooperate with the impression cylinders respectively, and means for driving said cylinders serving to drive one set of cooperating cylinders either in the same direction or in the opposite direction as compared with the other set of cooperating cylinders. 130
- 60 7. In a printing press, the combination of a heavy shaft, two impression cylinders in closely spaced end to end relation to each other on said shaft, a second heavy shaft located at one side of said first named shaft, two form cylinders in end to end relation on said second shaft 135
- 65 in position to cooperate with said impression cylinders respectively, and means for driving said cylinders in one direction and to drive the other set of cooperating cylinders in the opposite direction. 140
- 70 8. In a printing press, the combination of a heavy shaft, two impression cylinders in closely spaced end to end relation to each other on said shaft, a second heavy shaft arranged parallel with said first named shaft, two form cylinders in end to end relation on said second shaft in position to cooperate with said impression cylinders respectively, means for fastening one of said sets of cylinders to said shafts for 145
- 75 rotation therewith, means for driving said shafts in cooperative relation, and means driven from said shafts for rotating the other set of cooperating cylinders in the opposite direction. 150
9. In a printing press, the combination of a plurality of press units each comprising two printing couples for printing both faces of a web, a heavy shaft in spaced relation to said several units and in parallel relation to the cylinders of said units, two auxiliary impression cylinders in end to end relation on said shaft, a set of other shafts in spaced relation to each other about said first named shaft, two form cylinders in end to end relation on each of said other shafts, and means for driving the cylinders in opposite directions at opposite sides of the press. 155
10. In a printing press, the combination of a plurality of press units each comprising two printing couples for printing both faces of a web, a heavy shaft in spaced relation to said several units and in parallel relation to the cylinders of said units, two auxiliary impression cylinders in end to end relation on said shaft, a set of other shafts in spaced relation to each other about said first named shaft, two form cylinders in end to end relation on each of said other shafts, means for driving said shafts and the cylinders thereon at one side of the press in one direction, and other means actuated by said shafts for driving the cylinders at

the opposite side of the press in the reverse direction.

11. In a printing press, the combination of a plurality of press units each comprising two printing couples for printing both faces of a web, a heavy shaft in spaced relation to said several units and in parallel relation to the cylinders of said units, two auxiliary impression cylinders in end to end relation on said shaft, 5 a set of other shafts in spaced relation to each other about said first named shaft, two form cylinders in end to end relation on each of said other shafts, means for keying the cylinders at one side of the press on said shafts so as to 10 rotate therewith, means for driving said shafts in co-operative relation to each other, and means actuated by said shafts for driving the cylinders at the opposite side of the press in the reverse direction.
12. In a printing press, the combination of a plurality of press units each comprising two printing couples for printing both faces of a web, a heavy shaft in spaced relation to said several units and in parallel relation to the cylinders 25 of said units, two auxiliary impression cylinders in end to end relation on said shaft, a set of other shafts in spaced relation to each other about said first named shaft, two form cylinders in end to end relation on each of said other shafts, means for keying the cylinders at one side of the press on said shafts so as to rotate therewith, gears connecting said shafts for causing them to rotate in co-operative relation to each other, gears connected with the several 30 cylinders respectively at the opposite side of the press for causing them to rotate in co-operative relation to each other, and means connecting said last named gears with one of said shafts for causing the cylinders at one side of the press to rotate in the opposite direction from that in which the corresponding cylinders rotate at the 35 opposite side of the press.
13. In a printing press, the combination of a plurality of press units each comprising two printing couples for printing both faces of a web, a heavy shaft in spaced relation to said several units and in parallel relation to the cylinders of 40 said units, two auxiliary impression cylinders in end to end relation on said shaft, a set of other shafts in spaced relation to each other about said first named shaft, two form cylinders in end to end relation on each of said other shafts, means for keying the cylinders at one side of the press on said shafts so as to rotate therewith, gears connecting said shafts so as to rotate therewith, gears connecting said shafts for causing them to rotate in co-operative relation to each other, gears connected with the several cylinders respectively at the opposite side of the press for 45 causing them to rotate in co-operative relation to each other, and means connecting said last named gears with one of said shafts for causing the cylinders at one side of the press to rotate at the same speed as that at which the corresponding cylinders rotate at the opposite side of the press but in the opposite direction.
14. In a printing press, the combination of a plurality of press units each comprising two printing couples for printing both faces of a web, 50 an auxiliary impression cylinder and a plurality of co-operating form cylinders in spaced relation to each other about said impression cylinder at one side of the press for making an outside face color printing on a portion of any selected one of the webs from said press units, a second aux-

iliary impression cylinder and a plurality of co-operating form cylinders in spaced relation to each other about said impression cylinder at the opposite side of the press in axial alignment respectively with the first named auxiliary cylinders and in position to make an inside face color printing on a complementary web portion from said press units, means for driving said auxiliary cylinders serving to rotate the cylinders at one side of the press in the reverse direction from that at the opposite side of the press, and inking mechanisms at opposite sides of the press driven in opposite directions corresponding to the direction of rotation of the cylinders.

15. In a printing press, the combination of a plurality of press units each comprising two printing couples for printing both faces of a web, an auxiliary impression cylinder and a plurality of co-operating form cylinders in spaced relation to each other about said impression cylinder at one side of the press for making an outside face color printing on a portion of any selected one of the webs from said press units, a second auxiliary impression cylinder and a plurality of co-operating form cylinders in spaced relation to each other about said impression cylinder at the opposite side of the press in axial alignment respectively with the first named auxiliary cylinders and in position to make an inside face color printing on a complementary web portion from said press units, means for driving said auxiliary cylinders serving to rotate the cylinders at one side of the press in the reverse direction from that at the opposite side of the press, axially aligned ink drums at opposite sides of the press driven in opposite directions corresponding to the direction of rotation of the cylinders, means at each side of the press for applying and distributing ink on said drums, and means for transferring the ink from each of the said drums to the adjacent form cylinder.

16. In a printing press, the combination of a plurality of press units each comprising two printing couples for printing both faces of a web, a heavy shaft in spaced relation to said several units and in parallel relation to the cylinders of said units, two auxiliary impression cylinders in end to end relation on said shaft, a set of other shafts in spaced relation to each other about said first named shaft, two form cylinders in end to end relation on each of said other shafts, means for driving the cylinders in opposite directions at opposite sides of the press, a second set of other shafts spaced about said first named shaft at greater distances therefrom than said first named set, two ink drums in end to end relation on each of said last named shafts and driven in opposite directions corresponding to the direction of rotation of the adjacent cylinders, means at each side of the press for applying and distributing ink on said drums, and means for transferring the ink from each of said drums to the adjacent form cylinder.

17. In a printing press, the combination of a plurality of press units each comprising two printing couples for printing both faces of a web, a heavy shaft in spaced relation to said several units and in parallel relation to the cylinders of said units, two auxiliary impression cylinders in end to end relation on said shaft, a set of other shafts in spaced relation to each other about said first named shaft, two form cylinders in end to end relation on each of said other shafts, means for driving the cylinders in opposite directions at opposite sides of the press, a

second set of other shafts spaced about said first named shaft at greater distances therefrom than said first named set, two ink drums in end to end relation on each of said last named shafts 5 and driven in opposite directions corresponding to the direction of rotation of the adjacent cylinders, an additional set of shafts spaced with respect to each other about each of the shafts on which said ink drums are mounted, means for applying ink to said ink drums, ink rollers on some

of said last named shafts at one side of the press in position for cutting and spreading the ink on the ink drum at that side of the press, other ink rollers on the other of said last named shafts at the opposite side of the press in position for cutting and spreading the ink on the ink drum at the corresponding side of the press, and means for transferring the ink from each of said drums to the adjacent form cylinder. 80
